United States Patent Office

Des. 204,994
Patented June 7, 1966

204,994

GOBLET OR SIMILAR ARTICLE

Bill G. Moomey, Waukesha, Wis., assignor to Jos. Schlitz
Brewing Company, Milwaukee, Wis., a corporation of Wisconsin

Filed May 26, 1965, Ser. No. 85,474

Term of patent 14 years

(Cl. D36—8)

FIGURE 1 is a side elevation of a goblet or similar article, showing my new design; and

FIG. 2 is a top plan view thereof.

I claim:

The ornamental design for a goblet or similar article, substantially as shown.
